ARTHUR GILBERT, OF TERRA HAUTE, INDIANA, ASSIGNOR OF ONE-THIRD TO HARRY JEMUNE AND ONE-THIRD TO HIRAM E. BOOTS, BOTH OF GREENUP, ILLINOIS.

COMBINED CIGARETTE AND MATCH BOX.

1,297,831.

Specification of Letters Patent. Patented Mar. 18, 1919.

Application filed July 9, 1917. Serial No. 179,540.

To all whom it may concern:

Be it known that I, ARTHUR GILBERT, a citizen of the United States, residing at Terra Haute, in the county of Vigo and State of Indiana, have invented new and useful Improvements in Combined Cigarette and Match Boxes, of which the following is a specification.

This invention relates to a box of the type wherein a casing has mounted to slide therein a cigarette tray in which is arranged a receptacle for matches.

The primary object of the invention is to provide an improved box of this character in which the receptacle for the matches is so constructed as to facilitate the withdrawal of a match therefrom, particularly, when the hands of the smoker are incased in gloves.

Another object of the invention is to provide the box with a tray wherein the match receptacle is so arranged within the tray and is of such length as to permit partially consumed cigarettes to be returned to the tray and carried therein beneath the match receptacle without being exposed to view when the box is opened to obtain a cigarette which has not been lighted, or a match.

With these and other objects in view, the invention resides in the novel combination and arrangement of parts, which will be hereinafter described and particularly pointed out in the claim.

The preferred embodiment of the invention has been illustrated in the accompanying drawings, although no restriction is necessarily made to the precise details of construction therein shown, as changes, alterations, and modifications within the scope of the claim may be resorted to when desired.

In the drawing:

Figure 1 is a perspective view of a combined cigarette and match box constructed in accordance with the invention wherein the cigarette tray is shown partly withdrawn from the casing.

Fig. 2 is a horizontal section on the line 2-2 of Fig. 1.

Fig. 3 is a vertical longitudinal section through the box.

Fig. 4 is a perspective view of the cigarette tray and match receptacle associated therewith.

Referring now to the drawing in detail, the letter A designates a combined cigarette

and match box which may be formed from any suitable material, such as cardboard, or the like, and wherein an open ended casing B of rectangular shape has mounted to slide therein a cigarette tray C in which is arranged a match receptacle D.

The tray C is formed from a blank which includes a rectangular shaped body portion 10 from the sides of which extend flaps 11, 12, 13, and 14, with each of the flaps 11 and 12 scored to form panels 15 and tongues 16 and 17 upon the flaps 11 and 12, the panels 15 together with the flap 14 forming an end and side walls of the tray, while the tongues 16 and 17 are adapted to partially close one side of the tray when the tray is arranged in the casing B.

The flap 13 is scored to form a pair of panels 18 and 19 of less length than the flap 13 and a panel 20 extending transversely of the flap at one end of the panel 18, said panels 15, 18, 19, and 20 on the flap 13 together with the body portion 10 of the tray forming within the tray, the open topped match receptacle D, the panels 19 and 20 having formed thereon wings 21 which are secured to the body portion 10 of the tray in any suitable manner.

The end walls of the receptacle D which are formed by the panels 15 and 19 of the flap 13 are beveled at their upper ends as shown to space the upper edge of the front side wall of the receptacle D below the upper edge of the body portion 10 of the tray, said upper edge of the front wall of the receptacle D being curved as shown to enable the matches within the receptacle to be easily grasped between the thumb and finger when it is desired to withdraw a match therefrom.

The bottom of the receptacle D which is formed by the panel 20 inclines upwardly and rearwardly from the lower edge of the front side wall of the receptacle D, so that the heads upon one row of matches within the receptacle D will be spaced above the heads on the row of matches in front thereof, thus enabling a match to be easily withdrawn from the receptacle D, particularly, when the smoker's hands are incased in gloves.

The receptacle D is of such length as to extend only half the length of the tray C, so that when cigarettes are arranged upon the tray between the flap 14 and receptacle D, a space 22 is left within the tray below

the receptacle D in which may be arranged partly consumed cigarettes as shown in Fig. 3 in the drawing, with the cigarette retained in the space 22 through the engagement with 5 the upper end of the cigarette and the inclined bottom of the receptacle C, the tongue 17 on the flap 12 serving to conceal the partly consumed cigarette from view when the tray is extended beyond an end of the casing B 10 as shown in Fig. 1 in the drawing.

At this point, I wish to call attention to the fact that with the boxes of this character now in use, the receptacles D extend the entire length of the box, and as the tray is of 15 greater length than the matches now in common use, the box must be inverted for the withdrawal of a match from the holder, furthermore, with the boxes now in use to enable the greater portion of the space within 20 the tray to be utilized for cigarettes, the match holder is made exceedingly narrow which greatly reduces the match holding capacity of the box as well as rendering the withdrawal of matches from the box, ex- 25 ceedingly difficult when the smoker's hands are incased in gloves.

The panel 15 of the flap 11 has secured thereto in any suitable manner above the open top of the receptacle D, an abrading 30 strip 23 upon which the matches withdrawn from the receptacle may be struck.

When the box A is in use and it is desired to remove a cigarette therefrom, the tray is moved to the position shown in Fig. 1 in the 35 drawing and a cigarette extracted therefrom, after which, a match may be withdrawn from the receptacle D and struck upon the abrading strip 23 to light the match.

40 Should the smoker desire to board a car,

or enter a building in which smoking is prohibited before the cigarette which was extracted from the box has been entirely consumed, he may extinguish the cigarette and place the same within the space 22 in which 45 it will be concealed from view by the flap 17 should the tray be again moved to a position as shown in Fig. 1, thereby preventing the smoker from becoming embarrassed by the exposure to view of the partially consumed 50 cigarette should he desire to offer a friend a cigarette from the tray.

From the foregoing description, taken in connection with the accompanying drawing it is at once apparent, that a combined cigarette and match box has been provided wherein the match receptacle is so constructed as to not only facilitate the withdrawal of matches therefrom but enables a space to be formed within the box in which partly consumed cigarettes may be carried. 55

Having thus described the invention, what is claimed as new is:

In a device of the class described, a tray comprising a body portion, flaps formed at the edges of said body portion, panels formed on one of said flaps, said panels being of less length than the flap to which they are secured and being located at one end of the said flap to provide a match receptacle 65 in one corner of the tray with a space beneath and at the side of the match receptacle, one panel of the receptacle having an inwardly curved transversely extending recess in its upper edge and panels formed on and extending entirely across opposite flaps 70 to provide closures for the tray. 75

In testimony whereof I affix my signature.

ARTHUR GILBERT.
